UNITED STATES PATENT OFFICE

2,690,614

CAN PUNCH

Floyd D. Lee, Pontiac, Mich.

Application August 8, 1952, Serial No. 303,357

1 Claim. (Cl. 30—6.1)

1

This invention relates to improvements in devices for punching openings in cans, such as milk cans, in order to permit dispensing of the contents thereof.

Another object of the invention is to provide a can punch which will accommodate the cans of different sizes.

Still another object of the invention is to provide a can punch which will punch two holes simultaneously and with but little effort on the part of the operator.

A further object of the invention is to provide a can punch of such simple construction as to permit its manufacture at a very low cost.

These and other objects and advantages of the invention will become apparent to the reader of the following description.

In the drawings:

Figure 1 is a top plan view of the implement.

Figure 2 is a side elevational view of the device.

Figure 3 is a longitudinal sectional view taken approximately on line 3—3 of Figure 1.

Figure 4 is a cross sectional view taken on line 4—4 of Figure 1.

Referring to the drawing, wherein like numerals designate like parts, it can be seen that the device is formed from three pieces of heavy gauge wire material. The large piece is formed to provide an annulus 10 from which extends a pair of arms 11, 11, preferably in the diverged relation shown in Figure 1, the ends being curved inwardly as at 12, 12 and welded or otherwise secured together as at 13. These factors 11, 11, 12, 12 and 13 serve to form a handle generally referred to by numeral 14.

A second shorter wire member 15 extends across the annulus 10 in longitudinal alignment with the handle 14 and has one end resting upon the annulus 10 while the other end is interposed between the arms 11, 11 at the points where these arms meet the annulus 10, this portion of the member 15 being denoted by numeral 16 and this portion 16 is welded or otherwise secured to these adjacent portions of the arms 11, 11.

The other end of the member 15 is welded or otherwise secured to the most distant part of the annulus 10 and each end of the member 15 is upturned and pointed to provide a punch 17.

At right angles to the member 15 is disposed a second punch member 18, this being disposed at the bottom of the annulus 10 and welded at its

2

ends not only to the annulus 10 but also to a medial point of the member 15.

The member 18 at its ends is provided with down-turned portions which are sharpened to provide punches 19, 19.

Thus the entire punching implement is formed from three pieces of heavy gauge wire, the annulus 10 and handle 14 being of one piece, while the second largest piece 15 takes care of punching 10 large size cans, while the smallest length member 18 takes care of punching openings in smaller cans.

In the use and operation of this device, the annulus 10 is simply placed over the top of a can 15 such as a milk can and then palm of a hand is placed over the members 15, 18 and a gentle push downwardly will cause the punches 19, 19 to form openings in the can top.

For larger cans, the implement need only be 20 rotated and the punch points 17, 17 employed.

Obviously the open neck can be hung over a nail or any other supporting member, or if desired within an implement drawer.

While the foregoing description sets forth the 25 invention in specific terms, it is to be understood that numerous changes in the shape, size and materials may be resorted to without departing from the spirit and scope of the invention as claimed hereinafter.

Having described the invention what is claimed 30 as new is:

A device of the character described comprising an open-ended wire ring, a pair of outwardly divergent wire arms each formed integrally with one end of said ring, inwardly curved interconnected outer ends for said arms, a longitudinally extending wire affixed at one end to said ring at a point diametrically opposed to the open end thereof and extending between and affixed to the inner portions of said arms, and a pointed punch extending perpendicularly in the same direction from each end of said longitudinal wire.
